UNITED STATES PATENT OFFICE.

THOMAS HAROLD BROWN, OF PHILADELPHIA, PENNSYLVANIA, ASSIGNOR TO E. E. BROWN & CO., INC., OF PHILADELPHIA, PENNSYLVANIA, A CORPORATION OF PENNSYLVANIA.

CORE-FORMING APPARATUS.

Application filed August 29, 1923. Serial No. 659,886.

To all whom it may concern:

Be it known that I, THOMAS HAROLD BROWN, a citizen of the United States, residing in the city of Philadelphia, county 5 of Philadelphia, and State of Pennsylvania, have invented certain Improvements in Core-Forming Apparatus, of which the following is a specification.

My invention is an improved apparatus 10 for forming cores for use in casting, and it is particularly adapted for the production of apertured cores having characters or indicia therein for reproduction on the castings, as sash weights, formed therefrom.

15 The leading objects of my invention are the improvement of the quality of the cores and castings formed and the simplification of the apparatus. By my improvements, the crumbling of the edges of the core is avoided and a core formed from which a casting, as a sash weight, may be formed having a curved nonabrading bearing for a cord and displaying a character denoting, for instance, its weight or quality. My improved apparatus comprises few and simple pieces and eliminates the necessity for springs and spacers heretofore required.

In its preferred form, my invention is embodied in a single piece core box or mold 20 having lateral openings through which cooperating molding bars are introduced and removed, such members preferably being longitudinally tapered and one thereof comprising a fixed member preferably having 25 a curved surface which gives to the core and the casting made therefrom a curved bearing for the engagement of a cord.

The characteristic features of my improvements will more fully appear from the following description and the accompanying drawings of a preferred embodiment thereof.

In the accompanying drawings, Fig. 1 is a side elevation, partly in section, of apparatus embodying my invention; Fig. 2 is a top view taken on the line 2-2 of Fig. 1; Fig. 3 is a perspective view of the character bearing molding bar; Fig. 4 is a perspective view of a core formed in my apparatus, and Fig. 5 is a perspective view of a sash weight produced with the use of the core shown in Fig. 4.

As illustrated in the drawings, a base 1 has thereon a post or pedestal 2 to which is

55 bolted a longitudinally tapered molding bar 3 secured in place by a nut 4, and having a curved lower surface 3' and a flat upper surface 3''. A one-piece core box 5 contains a recess socket 6 having an open end and surrounded by the wall 7, the latter containing the diametrically opposite apertures 8.

A second molding bar 9, having a longitudinal taper complementary to the taper of the molding bar 3, has thereon an embossed character 10, and is provided with a stop 11.

In assembling the apparatus for the formation of a core, the molding bar 9 is inserted through the apertures 8 of the core 70 box until the stop 11 engages the wall 7, when the character 10 is centered in the aperture 6. The core box, with the molding bar 9 therein, is then slid over the upper surface 3'' of the molding bar 3 until the 75 end of the bar 9 engages the nut 4. Sand is then rammed in the core box about the molding bars and forms a core, such as illustrated in Fig. 4, having a body 12 containing an aperture 13 spanned by a bridge 14. 80 The aperture has a flat surface 15 with the intaglio character 10' therein and the curved surface 16 conforming with the curvature of the surface 3'. When the core is used for casting a sash weight such as shown in Fig. 85 5, the metal entering the core aperture 13 forms a cross bar 17 having a flat end 18 bearing the character 10'', indicating for instance the number of pounds in the sash weight, and a curved surface 19 providing 90 a non-abrading bearing for the sash cord.

When the core is ready for removal from the core box, the latter, with the molding bar 9, is moved along the molding bar 3, the tapered formation of the molding bars facilitating the removal and avoiding breakage of the core edges. When the parts have been removed from the molding bar 3, the molding bar 9 is lowered sufficiently to disengage the character 10 from the sand then 100 moved longitudinally out of the box.

Having described my invention, I claim:

1. Core forming apparatus comprising a core box having an apertured wall and oppositely tapered molding bars independently movable longitudinally through said wall.
2. Core forming apparatus comprising a

one-piece core box having an apertured wall and molding bars movable through said wall, one of said bars having a curved surface, and one of said bars having a character design thereon, said bars together having substantially the same cross sectional area at the opposite sides of said core box.

3. Core forming apparatus comprising a core box having an apertured wall and 10 molding bars independently movable longitudinally through said wall, one of said bars carrying a character and the other bar having a curved surface, said bars having complementary tapers so that their combined cross sectional areas are substantially 15 the same throughout the core box.

4. Core forming apparatus comprising a

base, a molding bar fixed to said base, a core box having a wall containing opposite apertures movable on said molding bar, and 20 a second molding bar movable relatively to said box and to said bar first named.

5. Core forming apparatus comprising a base having connected therewith a tapered molding bar having a curved surface, a core 25 box having an apertured wall movable on said bar, and a second tapered molding bar carrying a character and movable longitudinally in said core box and relatively to said first bar. 30

Signed at Philadelphia, in the county of Philadelphia and State of Pennsylvania, this 27th day of August, 1923.

THOMAS HAROLD BROWN.
